END PROTECTOR

Filed Dec. 22, 1939

FIG. 1.

FIG. 2.

Inventor:
HOWARD M. HICKS,
by: John E. Jackson
his Attorney.

UNITED STATES PATENT OFFICE

2,238,642

END PROTECTOR

Howard M. Hicks, McKeesport, Pa., assignor to
 National Tube Company, a corporation of New
 Jersey

Application December 22, 1939, Serial No. 310,622

1 Claim. (Cl. 138—96)

This invention relates to end protectors, and more particularly to those which are used for protecting the threaded ends of pipes and tubes such as are used for well-casing, drill tubing, line pipe, or any tubular article wherein corrosion and mechanical injury to exterior threads or machined surfaces are undesirable.

In well drilling, for example, extreme accuracy must be maintained in preparing the joints in the string of drilling tools. However careful these joints are made at the place of manufacture, they are subject to possible damage in transit to the consuming site and while awaiting assembly after their arrival. If they are to be used for the purpose for which they are intended, they must be protected from exposure to moisture to prevent corrosion as well as from abrasion and mechanical injuries to the exterior threads and machined surfaces which are used in completing the joint.

It is among the objects of the present invention to provide an end protector for tubular articles having on the exterior ends thereof a screw-threaded, machined or otherwise prepared surface.

Another object is the provision of a device of the class described which is cheap to manufacture, easy to install and remove and one which is, at the same time, very durable in service.

The foregoing and other objects will be more apparent after referring to the drawing, in which:

Figure 1 is a sectional elevation of the device of the invention as it is used on the exteriorly threaded end of a male element of a drill tube; and

Figure 2 is an end view of the showing of Figure 1.

Referring more particularly to the drawing, the numeral 2 designates the end of a tubular article, such as the male element of a drill tube. In order to protect the exterior surfaces of the male element of the drill tube, which may be screw-threaded or machined in the manner well known in the art, the device of the present invention includes a split cup member 3 which, more specifically, comprises a pair of semi-cylindrical wall members 4, each of which terminates in a semi-circular right-angularly extending bottom portion 5. In other words, the semi-cylindrical wall members 4 and bottom portions 5, when in assembled relationship, form a cup which is split in half along lines indicated by the adjacent opposed surfaces 1. The center of the bottom of the cup 3, which is formed by the bottom portions 5, is provided with an aperture 8 which is taper-threaded for a purpose to be later described. In other words, each of the members 5 is provided with a semi-circular recess which is

screw-threaded on a taper, whereby the complementary screw-threaded surfaces form a taper-threaded aperture.

From the foregoing it will be seen that the sectional cup 3 comprising the cylindrical side walls 4 and the bottom portions 5 will seat into and snugly occupy the cylindrical bore of the tubular article 2.

Secured to the outer ends of the side walls 4 of the sectional cup 3 is a continuous right-angled flange 10 having integrally formed therewith a frusto-conical hood 11, the largest diameter of which is provided with an outwardly extending continuous radial flange 12. Disposed in contact with the outer face of the continuous radial flange 12 is a compressible gasket 13 which is adapted to seat against the shoulder 14 at the base of the tapered portion 15 of the joint forming instrumentality which, as before stated, may be either screw-threaded or machined.

In operation:

The sectional cup 3 is disposed within the cylindrical bore of the metallic tubular article 2 with the hood portion 11 extending over the joint forming instrumentality (threads or machine tapered surfaces) with the continuous radial flange 12 adjacent the shoulder 14 at the base of the joint forming instrumentality and with the gasket 13 disposed between the same. A taper-threaded plug 16 is screwed into the taper-threaded aperture 8 formed by the complementary semi-cylindrical tapered and screw-threaded surfaces at the center of the bottom portions 5 of the cup 3. The plug 16 is screwed into the said aperture 8 a sufficient distance to force the side walls 4 of the cup to snugly occupy the cylindrical bore of the tubular article 2.

While I have shown and described one specific embodiment of the present invention, it will be seen that I do not wish to be limited exactly thereto, since various modifications may be made without departing from the scope of the invention, as defined by the following claim.

I claim:

An end protector for the male element of a frusto-conical joint for a tubular article comprising, in combination, a segmental cup adapted to fit within the bore of the said tubular article, a radial flange on the outer end of said cup, a frusto-conical hood carried by said radial flange for covering said male element, a radial flange on the end of said frusto-conical hood, a gasket between said radial flange and the base of said male element, and a coniform screw-threaded plug extending through the bottom wall of said cup in screw-threaded engagement therewith whereby the segments thereof may be expanded into engagement with the bore of said tubular article.

HOWARD M. HICKS.
